(57) **CLAIM**

The ornamental design for a calibration device for a radar and an imaging device of a vehicle, as shown and described.

DESCRIPTION

(72) Inventor: **Zhenyu Cai**, Guangdong (CN)

(73) Assignee: **AUTEL INTELLIGENT TECHNOLOGY CORP., LTD.,**
Shenzhen, Guangdong (CN)

(**) Term: **15 Years**

(21) Appl. No.: **29/654,146**

(22) Filed: **Jun. 21, 2018**

G08G 1/166; G08G 1/167; G08G 1/168;

FIG. 1 is a front elevational view of a calibration device for a radar and an imaging device of a vehicle showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof.
